UNITED STATES PATENT OFFICE.

EDMUND L. MOORE, OF MEDFORD, MASSACHUSETTS.

PUMP.

Application filed April 14, 1924. Serial No. 706,244.

This invention relates to pumps and has for its object to provide a novel pump for pumping air, gas or other fluid into a container under relatively small pressure.

5 The device is useful for various purposes among which may be mentioned that of filling toy balloons or other similar articles with air or gas under suitable pressure.

The device comprises an expansible and 10 contractible chamber having an inlet and an outlet, an inwardly opening check valve in the inlet, an outwardly opening check valve in the outlet, and a connecting member at the outlet arranged to have the balloon 15 or other container to be filled connected thereto so that by alternately contracting and expanding the chamber the air, gas or other fluid may be pumped into the container.

Toy balloons are usually made with a neck 20 portion through which they may be filled and after being filled the neck is closed by winding a string or cord around the same.

Another feature of my invention relates to a novel cord guide which is associated 25 with the connecting member and which facilitates the tying of the string or cord around the neck of the inflated balloon.

Other features of my invention will be 30 more fully hereinafter set forth in the following description of the selected embodiment of the invention which is illustrated in the drawings.

Fig. 1 of the drawings is a longitudinal 35 sectional view through a pump embodying my invention;

Fig. 2 is a view of a reduced scale showing the device in use for inflating a toy balloon;

Fig. 3 is a detail of the cord guide.

My improved pump comprises an expansible and contractible chamber which may conveniently be in the form of a compressible bulb 1 although so far as the invention is concerned this chamber might have any suitable construction which permits it to be 40 expanded and contracted. For convenience, however, I will refer to the chamber as the bulb. The expansible and contractible chamber has an inlet 2 and an outlet 3 and if it is made in the form of a bulb the latter will preferably be of a size to be held in the hand and of some resilient material so that it can be collapsed by pressure in a manner similar to that in which the rubber bulb of a syringe is operated. The inlet 45 and outlet 2 and 3 may be formed integral

with the bulb or may be formed of separate connections applied thereto.

In the construction herein shown the bulb has at each end a neck or conduit 4 into each of which is inserted one end of a connecting sleeve 5 of metal, hard rubber or similar material, the other end of one of the sleeves 5 being inserted into the inlet connection 2 and the other end of the other sleeve 5 being inserted into the outlet connection 3. The inlet connection 2 has therein an inwardly opening check valve 6 of any suitable construction and the outlet 3 has therein an outwardly opening check valve 7 which also may be of any desirable construction.

With this arrangement it will be observed that when the bulb 1 is compressed the air or gas therein will be forced through the outlet 3, since the inlet check valve 6 will prevent the gas from being forced backwardly through the inlet. When the bulb is released and it expands to its position shown in Fig. 1 the outlet check valve 7 will close and the suction created will draw gas, air or other fluid through the inlet check valve 6. By alternately compressing and releasing the bulb, therefore, gas or other fluid will be drawn in through the inlet and forced outwardly through the outlet.

The outlet has secured thereto a connecting member 8 to which the neck 9 of the toy balloon 14 or other container may be secured. The connecting member herein shown is formed with two portions 10 and 11 of different diameter, each portion having a 70 groove 12 formed on the exterior thereof.

The grooves 12 are adapted to receive the bead 13 that is formed around the neck of the toy balloon, either groove serving to retain the balloon in place while it is being inflated. The purpose of having the connecting member 8 with the two parts of different diameters is to accommodate balloons of different sizes. Some balloons have larger necks than others and by this arrangement 80 a balloon with either a large or a small neck may be applied to the connecting member.

After the toy balloons have been filled the necks 9 are closed by winding and tying a string or cord around them and in order to 85 facilitate this operation I have provided a cord guide 15 in the form of a finger which is pivoted to the connecting member 8 as shown at 16 so that it may be swung from the full to the dotted line position Fig. 1. 90

This cord guide is provided at its end with a guide eye 17 through which extends a cord 18 for use in tying the neck 9 of the balloon. The cord guide also is provided with a slit 19 into which one end of the cord may be caught as shown in Figs. 1 and 3.

In using the device the end of the connecting member will be inserted into the neck of the balloon as shown in the drawings so that the bead 13 on the balloon neck will be received in one of the grooves 12. The bulb is then alternately compressed and released thereby pumping air or other gas into the balloon and inflating the latter.

15 When the balloon has been properly inflated a cord 18 is threaded through the eye 17 and the end of the cord is caught in the notch 19 as shown and then the cord-guiding arm is swung into the dotted line position Fig. 1 or full line position Fig. 3. The length of the arm 15 is such that when it is in the full line position Fig. 3 the eye 17 thereof is situated beyond the end of the connecting member and the cord therefor is in position to be wrapped around the neck 9 of the balloon beyond said connecting member.

The operator may hold the pump in one hand and may grasp the cord with the other hand and wind it around the neck of the balloon, the end of the cord being held meanwhile in the notch 19 and the finger or arm 15 retaining the cord in position to wrap properly around the balloon neck. After the cord is thus wound around the neck and the latter is closed tight the end of the cord may be detached from the slot 19 and dethreaded from the eye 17 and then tied so as to permanently close the neck of the balloon.

40 It is sometimes desirable to fill these toy balloons with some gas other than air and to facilitate this operation I have shown the inlet 2 as formed at its end with a connecting member 20 which is adapted to be slipped over the end of a pipe leading to some source of gas supply. When the pump has thus been connected to such a pipe then it may be operated as above described for filling the balloon.

45 While I have described herein the pump as used for filling balloons yet I desire to state that the invention is equally applicable for filling other containers and, therefore, do not wish to be limited to any particular use.

I also desire to state again that while the bulb 1 forms a convenient expansible and contractible chamber yet the invention is not limited to the use of a bulb as any suitable chamber which will expand and contract may be used.

I claim:

1. A device for inflating toy balloons, said device including a conduit through which gas is delivered to the balloon, said

conduit having a connection at its discharge end to which the balloon is connected, and a cord-guiding arm at said discharge end and adapted to hold the cord in position to be wound around the neck of the balloon when the latter is filled.

2. A device for inflating toy balloons, said device including a conduit through which gas is delivered to the balloon, a connection at the discharge end of the conduit to which the balloon is secured, and a cord-guiding arm pivoted to said connection and adapted to hold a cord in position to be wrapped around the neck of the balloon when the latter is filled.

3. A device for inflating toy balloons, said device including a conduit having a discharge end, a connecting member at said discharge end adapted to have a toy balloon secured thereto and a cord-guiding arm pivoted to the connecting member and having means for gripping a cord, and also having a guide eye through which the cord may be threaded and which holds the cord in position to be wrapped around the neck of the filled balloon.

4. A device for filling balloons and similar containers, said device being provided with a conduit through which gas is delivered to the balloons, a connection at the discharge end of the conduit adapted to have a balloon secured thereto and provided with means for holding the end of a cord which is to be wrapped around the neck of the balloon after it is filled.

5. A pump for inflating toy balloons comprising an expansible and contractible chamber having an inlet and an outlet, the inlet being provided with a connection arranged to be slipped over and to tightly fit an ordinary gas jet or gas cock, said outlet being provided with a connection constructed to have the neck of a balloon secured thereto, an inwardly-opening check valve in the inlet and an outwardly-opening check valve in the outlet.

6. A device for inflating toy balloons comprising a member shaped at one end to have the neck of a balloon to be inflated secured thereto, said member having an opening through which the balloon may be filled, and a cord-guiding arm associated with said member and adapted to hold in position the cord to be wound around the neck of the balloon when the latter is filled.

7. A device for inflating toy balloons comprising a member shaped at one end to have the neck of a balloon to be inflated secured thereto, said member having an opening through which the balloon may be filled, and a cord-guiding arm pivoted to said member and adapted to hold the cord in position to be wrapped around the neck of the balloon when the latter is filled.

8. A device for inflating toy balloons

comprising a member shaped at one end to have the neck of a balloon to be inflated secured thereto, said member having an opening through which the balloon may be filled, and a cord-guiding arm pivoted to said member and having means for gripping the cord and also having a guide eye through which the cord may be threaded and which holds the cord in position to be wrapped around the neck of the filled balloon.

9. A device for inflating toy balloons comprising a member shaped at one end to have the neck of a balloon to be inflated

secured thereto, said member having an opening through which the balloon may be filled, and a cord-guiding arm pivoted to said member and having means for gripping a cord and also an eye at its end through which the cord extends, said arm being of such length that when it is in operative position the portion of the cord extending from the eye is in position to be wrapped around the neck of the filled balloon.

In testimony whereof, I have signed my name to this specification.

EDMUND L. MOORE.
